(57) CLAIM

I claim the ornamental design for the hair band and glasses holder, as shown and described.

DESCRIPTION

FIG. 1 is a front isometric view of the hair band with glasses holder of the patent invention.

FIG. 2 is a side plan view thereof.

FIG. 3 is a side plan view thereof.

FIG. 4 is a side plan view thereof.

FIG. 5 is a side plan view thereof.

FIG. 6 is a top plan view thereof.

FIG. 7 is a bottom plan view thereof; and,

FIG. 8 is an alternate front isometric view thereof.
